REFRIGERATOR CABINET OR SIMILAR ARTICLE

Raymond Loewy, New York, N. Y., assignor to General Motors Corporation, Dayton, Ohio, a corporation of Delaware

Application May 11, 1950, Serial No. 9,863

Term of patent 7 years

(Cl. D67—3)

To all whom it may concern:

Be it known that I, Raymond Loewy, a citizen of the United States, residing at New York city, in the county of New York and State of New York, have invented a new, original, and ornamental Design for a Refrigerator Cabinet or Similar Article, of which the following is a specification, reference being had to the accompanying drawing forming part thereof.

In the drawing:

Fig. 1 is a perspective view of a refrigerator cabinet showing my new design;

Fig. 2 is a top plan view thereof;

Fig. 3 is a side view of one part of the two part lid shown on the cabinet;

Fig. 4 is a rear view of the lid part shown in Fig. 3; and

Fig. 5 is an enlarged perspective view of a portion of the lid.

This application is a continuation-in-part of my copending application Serial No. D2549.

The dominant features of the design reside in the portions shown in full lines.

I claim:

The ornamental design for a refrigerator cabinet or similar article, as shown and described.

RAYMOND LOEWY.
